OUTBOARD PROPELLER MECHANISM

Arthur W. Wanzer, Quincy, Mass., assignor to
 Murray & Tregurtha, Inc., Quincy, Mass., a
 corporation of Massachusetts

Application January 3, 1949, Serial No. 68,817

1 Claim. (Cl. 115—18)

1

This invention relates to outboard propeller mechanism for boats, barges and the like of the type in which the propeller is mounted on a horizontal propeller shaft that is carried at the lower end of a vertically disposed propeller-supporting member, which in turn is mounted for turning movement about a vertical axis for steering the boat, said propeller shaft being connected by beveled gears to a vertical drive shaft which is driven from the power unit.

An outboard propeller mechanism of this type is illustrated in the Mathewson Patent No. 2,335,597, November 30, 1943, and also in my co-pending applications Serial No. 475,744, filed February 13, 1943, now U. S. Patent No. 2,458,813, and Serial No. 564,213, filed November 20, 1944, now U. S. Patent No. 2,499,339.

In the devices shown in said patent and applications the propeller-supporting member is given its turning movement for steering the boat by means of a worm gear which is rigidly mounted thereon at its upper end and which meshes with and is driven by a worm that is operatively connected to the steering wheel, so that by manipulation of this steering wheel the propeller-supporting member can be turned to steer the boat.

If in the operation of the propeller mechanism the propeller strikes an obstruction which holds it against turning movement, the torque transmitted from the power unit through the vertical driving shaft will apply a turning moment to the propeller-supporting member which is resisted by the intermeshing worm gear and worm.

The strain to which said worm gear and worm are thus subjected may be sufficient to strip the teeth of the gears and thus put the steering mechanism out of commission.

It is an object of the present invention to provide an outboard propeller mechanism which is constructed so as to prevent any stripping of or damage to the gears whenever the propeller is held from turning movement by striking an obstruction.

Another object of the invention is to provide an outboard propeller mechanism in which whenever the propeller does strike an obstruction which holds it from turning, the torque transmitted from the power unit to the vertical drive shaft will expend itself in turning the propeller-supporting member about its vertical axis, thereby freeing the propeller from the obstruction.

Such turning movement of the propeller-supporting member as may be occasioned by the propeller striking an obstruction will, of course, result in changing the direction of the boat, and

another object of the invention is to provide means for indicating to the helmsman whenever, and the extent to which, the propeller-supporting member has been turned by such obstruction, so that the helmsman may, by manipulating the steering wheel, bring the propeller-supporting member back to the proper position for maintaining the boat on its prescribed course.

In the drawings:

10 Fig. 1 is a view showing a boat, barge, or other vessel having my improved propeller mechanism mounted thereon;

15 Fig. 2 is an enlarged vertical section through the lower portion of the gear housing and the upper portion of the propeller-supporting housing;

Fig. 3 is a section on a reduced scale on the line 3—3 Fig. 2;

20 Fig. 4 is a detail of the transmission gearing in the gear housing;

Fig. 5 is a section on the line 5—5 Fig. 1, showing in dotted lines the position the propeller-supporting housing may assume when the propeller strikes an obstacle;

25 Fig. 6 is a detail of the steering mechanism.

In the drawings 1 indicates a boat, barge, or other sea-going vessel which is equipped with my improved propeller mechanism, the latter being of that type which includes a power generator 2, preferably an internal combustion engine, which is mounted on a suitable base 3 that in turn is mounted on the deck of the barge, and which has a power shaft 4 that is geared to an outboard vertically extending drive shaft 5 by which the propeller 6 is driven.

30 The propeller is carried by a propeller shaft 7 which is journaled in the propeller-supporting housing 8 and is connected to the drive shaft 5 through bevel gears 46. The drive shaft 5 is located within the housing 8 and the latter is mounted for turning movement about a vertical axis for steering the vessel.

35 The transmission gearing connecting the vertical drive shaft 5 and the power shaft 4 is a bevel gear transmission, such as shown in Fig. 4, which includes a bevel gear 9 on the end of the power shaft, another bevel gear 10 on the upper end of the drive shaft 5, and connecting bevel gears 11 operating on a horizontal axis. This bevel gear transmission is housed in a gear housing 12 which is supported by the base 3.

40 As stated above, the propeller-supporting housing 8 is mounted for turning movement about a vertical axis and for this purpose the upper end 13 of the propeller-supporting housing

8 extends into a depending portion 14 of the gear housing 12, said upper end 13 of the propeller-supporting housing being mounted in suitable roller bearings 15.

The steering mechanism for turning the propeller-supporting housing 8 in order to steer the boat, is similar to that shown in the above mentioned patent and applications, and it comprises a worm gear 16 secured to the upper end of the propeller-supporting housing 8 and which meshes with and is operated by a worm 17 carried on a transverse shaft 18 journaled in the gear housing 12. The shaft 18 has a sprocket 19 thereon that is connected by a sprocket chain 20 with a sprocket 21 on a short shaft 22 that is coaxial with the bevel gears 11 and which carries a bevel gear 23 that meshes with a companion bevel gear 24 on a longitudinally extending shaft 25. The shaft 25 is connected by a sprocket chain 26 with the shaft 41 carrying the steering wheel 48 so that turning movement of the steering wheel operates through the mechanism above described to turn the worm gear 16 and thus turn the propeller-supporting housing 8.

The parts thus far described may be similar to corresponding parts illustrated in the above mentioned patent and applications.

If during the operation of the propeller mechanism the propeller 6 strikes an obstacle which prevents its further rotation, the torque transmitted through the drive shaft 5 will apply through the gears 46 a strong turning moment to the propeller-supporting housing 8 tending to turn it about its vertical axis, which turning moment is resisted by the intermeshing worm 17 and worm gear 16.

Under some circumstances this turning moment may be of such force that the strain to which the worm 17 and worm gear 16 are subjected is sufficient to strip the teeth of the worm or the worm gear, or otherwise damage these parts.

In order to prevent such an occurrence I have connected the worm gear 16 to the upper part of the propeller-supporting housing 8 by means of a non-positive driving connection which is constructed so that normally it transmits sufficient torque from the worm gear 16 to the propeller-supporting housing 8 to provide for steering the boat, but which will yield and allow the propeller-supporting housing to be turned about its vertical axis by the torque transmitted thereto through the vertical drive shaft whenever the propeller strikes an obstruction that stops it from rotation. The worm gear 16 is in the form of a ring gear that rests on a seat 27 formed on a head element 28 that is secured to the upper end of the propeller-supporting housing 8 by means of bolts or screws 29.

The worm gear 16 is frictionally clamped to the seat 27 by means of a clamping plate 30 which is clamped to the head 28 by means of clamping screws 31. The upper face 32 of the worm gear 16 is shown as beveled and the clamping plate 30 has a corresponding beveled face 33 which engages the face 32 of the ring gear.

By this means the ring worm gear 16 is frictionally clamped to the head 28, which in turn is rigidly secured to the upper end of the propeller-supporting housing 8. The frictional clamping pressure thus obtained is sufficient to transmit from the worm gear 16 to the propeller-supporting housing sufficient torque for turning said housing for the purpose of steering the boat.

If, however, the propeller strikes an obstacle and is held thereby from turning, the torque to

which the propeller-supporting housing 8 is subjected by the power delivered through the drive shaft 5 will be sufficient to overcome the frictional clamping pressure of the clamping member 30 against the worm gear 16 and said propeller-supporting housing 8 will thus be turned about its vertical axis relative to the worm gear 16. The clamping pressure of the clamping member 30 against the worm gear will be so adjusted as to allow the turning movement of the propeller-supporting housing relative to the worm gear before the worm gear and worm are subjected to sufficient strain to damage them.

This operation of the propeller-supporting housing being turned about its vertical axis when the propeller strikes an obstruction, is illustrated in Fig. 5 wherein the full lines indicate the normal position of the propeller-supporting housing and the propeller 6, and the dotted lines indicate the position into which the propeller-supporting housing and propeller might be turned as described above when the propeller strikes an obstruction.

If the propeller-supporting housing and propeller is thus turned out of its normal position, as shown in dotted lines Fig. 5, the propeller will be in a position to turn the boat or vessel off from its prescribed course and under these circumstances it is necessary for the helmsman to manipulate the steering wheel 48 so as to restore the propeller-supporting housing and propeller to its proper position to maintain the boat on its course.

My improvements also include means to indicate to the helmsman whenever the propeller-supporting housing and the propeller have been thrown out of correct position by the propeller striking an obstacle, and also to indicate to the helmsman when the propeller-supporting housing has been restored to its correct position.

For this purpose the head 28 is provided on its periphery with a ring gear 34 the teeth of which mesh with a pinion 35 on a vertical shaft 36 carried by the gear housing 12. The shaft 36 is geared to a horizontal forwardly extending shaft 37 by means of suitable gearing, such as a spiral gearing 38, and the shaft 37 extends to and operates a suitable indicator 39 which is positioned where the helmsman can see it.

With this construction any turning movement of the propeller-supporting housing 8 about its vertical axis will be indicated on the indicator 39. If it be assumed that when the propeller-supporting housing 8 is positioned so that the propeller shaft 1 extends directly fore and aft, the pointed 40 of the indicator 39 will be centrally positioned, as shown in full lines Fig. 3, then if and when the propeller-supporting housing 8 is turned about its vertical axis relative to the worm gear 16, by reason of the propeller striking an obstruction as above described, such turning movement of the propeller-supporting housing will operate through the gears 34, 35, and 38 to turn the shaft 37 with the result that the pointer 40 of the indicator 39 will be turned in one direction

or the other, as shown by dotted lines. The helmsman can thus observe from the indicator the fact that the propeller-supporting housing has been turned about its vertical axis and the position of the pointer 40 will indicate the extent to which it has thus been turned. The helmsman will then manipulate the steering wheel 48 so as to restore the propeller-supporting housing to its correct position, and the resultant movement of the pointer 40 will indicate to the helms-

man when said propeller-supporting housing has been properly positioned for maintaining the boat on its prescribed course.

I claim:

An outboard propeller mechanism comprising a main supporting element, a propeller-supporting member depending therefrom, a propeller shaft carried by said propeller-supporting member, a propeller mounted on said propeller shaft, a power shaft, a vertically extending drive shaft operatively connecting said power shaft and propeller shaft, said propeller-supporting member being turnable about a vertical axis relative to the main supporting member for steering the boat, steering mechanism for turning said propeller-supporting member including a worm gear mounted thereon coaxially therewith, a worm meshing with the worm gear and a friction drive connection between the worm gear and the propeller-supporting member which provides sufficient torque to turn the propeller-supporting member for steering the boat when the steering

mechanism is operated but which slips and thus allows the propeller-supporting member to be turned about its axis relative to the worm gear and without disturbing the steering mechanism when the propeller is prevented from turning by striking an obstacle, and means separate from the steering mechanism to indicate the extent of any relative turning movement between the worm gear and said propeller-supporting member.
